RADIO RECEIVING SYSTEM

Frederick J. Ritter, Washington, D. C.

Application October 5, 1934, Serial No. 747,060

7 Claims. (Cl. 250—27)

This invention is a radio receiving system, and pertains more particularly to electron tube circuits for such systems, this case being a continuation in part of application Serial No. 531,806, filed April 21, 1931, Patent No. 2,037,485, April 14, 1936.

In radio receiving circuits of the prior art, employing electron discharge devices or vacuum tubes, it has almost universally been necessary to make use of a plurality of current sources in order to supply the filaments, plates and grids of the tubes with potential necessary for their operation. These sources have included a filament battery, a plate or "B" battery, and frequently, a grid or "C" battery. Such a multiplicity of current sources has rendered the circuits cumbersome and has interfered materially with supplying the elements of the vacuum tubes satisfactorily.

Alternating current sources for supplying the elements of vacuum tubes in such systems require various forms of filters to reduce noise which results from the use of an alternating current source. These filters are quite complicated and expensive, and are subject to breakdown which renders them unsatisfactory.

The main object of the present invention is to simplify the system by providing an electron discharge circuit for radio receiving systems in which a single-voltage alternating current source will have direct electrical connections with each of the circuits, which respectively include the filament, the plate and the grid.

The invention will be hereinafter fully described and particularly pointed out in the claims.

In the accompanying drawing:—

Figure 1 is a diagram of one form of radio receiving circuit embodying the invention, arranged to be supplied with alternating current from a single voltage source. Figure 2 is a detail view illustrating typical connections for a tube having a supplemental grid.

Referring to the drawing, the reference character 3 designates the usual antenna of a radio receiving circuit connected to a ground 6 through a condenser 4, having a resistance 5 shunted around it. Connected in parallel with the resistance and condenser are a tapped tuning coil 7 and a variable condenser 8, either or both of which may be adjusted to tune the aerial circuit to the frequency of incoming signals.

The detecting device here shown is a standard form of three-element vacuum tube 9, containing filament 10 of a cathode heater 10^a, plate 22 and grid 12. Current to the filament 10 is supplied

from a single alternating current source 24, such as a house lighting circuit through a step-down transformer 23, preferably adapted to supply a current of about six volts to the filament through the secondary 25. A higher voltage may be used if desired. 5

The current from the secondary 25 passes through the wire 11, to the primary coil 14 of a radio frequency transformer T. From the coil 14, a portion of the current passes through the 10 receiver 17 and conductor 27 to the plate 22.

The input or grid-filament circuit includes the aerial circuit, rheostat 13, cathode heater 10^a, filament 10, grid 12, wire 18, the secondary 19 of transformer T, and wire 21. As shown, the secondary 19 of transformer T, is shunted by a variable condenser 20, having a resistance shunted around it. This condenser improves the sharpness of tuning but is not essential and may be omitted if desired. 15

The out-put or plate-filament circuit includes one side of secondary 25 of step-down transformer 23, filament 10, wire 11, to the primary coil 14, of a radio frequency transformer T. From the coil 14, a portion of the current passes through 25 the receiver 17, thence through wire 27, plate 22, filament 10, and back to opposite side of secondary 25 of step-down transformer 23. 20

The drop in potential through the filament 10 is sufficient to establish a difference in potential 30 between the plate and the filament. This difference in potential is, however, increased by the drop in potential through the secondary 19, which is included in the filament circuit and has substantial resistance. 35

In the arrangement hereinabove described, the filament, the cathode, the plate and the grid are all supplied with current from the alternating current source through the secondary 25 of the step-down transformer 23. Ordinarily, in the 40 system as illustrated and described, the electron discharge device will function substantially as a rectifier and a hum eliminator. If, however, an additional device is necessary to assist rectification and to completely eliminate possible hum, 45 and to rectify the current, I make use of a combination hum eliminator and current rectifier 26. For this purpose, it has been found that a discharged dry cell containing manganese dioxide composition, is a very satisfactory hum eliminator 50 and current rectifier, and that by employing such eliminator, clear radio signals may be received. However, this hum eliminator and current rectifier ordinarily are not essential as such and may be omitted if desired. 55

When a tube of the "screen-grid" type which employs a supplemental grid is to be used, the circuit may be arranged as shown in Fig. 2. The parts as shown in Fig. 2 correspond exactly to those of Fig. 1 and are designated by the same reference characters, but a supplemental grid 29 is shown connected to the plate circuit by a lead 28. In adapting the circuit of Fig. 1 for use with a tube of this type, it is merely necessary to connect the terminal of the grid 29 in any convenient point in the plate or anode circuit, as shown.

The use of a combined radio and audio frequency transformer, such as the transformer T, in the manner above described renders the circuit particularly effective. The vacuum tube 9 may be of any standard form, and the circuit is adapted to operate satisfactorily with any of them.

Circuits embodying the invention are applicable to use, not only in receiving circuits as illustrated, but also amplifiers of general application, and in numerous other relations which will readily suggest themselves to persons skilled in the art.

It will be observed from the drawing that the circuits are so arranged in the apparatus as illustrated, that the total voltage of the source is applied to each of the filament, plate and grid circuits. Consequently, a predetermined voltage source may be employed and the apparatus may thereby be greatly simplified over circuits in which a plurality of sources of current are necessary. By means of the external circuit means directly connecting all of the elements of the electron discharge device with a single voltage source of low voltage alternating current, as herein shown and described, a decided advantage is gained in that the necessity for a separate plate circuit is avoided.

Having thus explained the nature of the invention and described an operative manner of constructing and using the same, although without attempting to set forth all of the forms in which it may be made, or all of the forms of its use, what is claimed is:—

1. A radio receiving set comprising means providing an antennae circuit, an electron discharge device provided with a plate, a grid, and a cathode, an input circuit therefor, means for connecting the input circuit with the antennae circuit, means providing a single circuit including a low-voltage-source of alternating current, together with connections therefrom to the plate, grid and filament of said electron discharge device such as to utilize said single-voltage-source for complete energization thereof, a metal core transformer, said single-voltage circuit being connected in series with the primary of said transformer and the plate, the secondary of the transformer being connected in series with the input circuit, and means providing an output circuit including connection from said plate to said single circuit.

2. A radio-receiving set comprising means providing an antennae circuit, an electron discharge device provided with a plate, a grid, a filament and a cathode heated by the filament, an input circuit therefor, means for connecting said input circuit with the antennae circuit, means providing a single circuit including a directly connected single-voltage-source of low voltage alternating current, connections therefrom to the plate, the grid, the filament and the cathode of said electron discharge device such as to utilize said single-voltage-source for complete en-

ergization thereof, a metal core transformer, said single-voltage-source being connected in series with the primary of said transformer, the filament and the cathode, the secondary of the transformer being connected with said input circuit, and means providing an output circuit including connection from the plate to said single circuit. 5

3. A radio-receiving set comprising means providing an antennae circuit, an electron discharge device provided with a plate, a grid, a filament, a cathode and a supplemental grid, an input circuit therefor, means for connecting said input circuit with the antennae circuit, means providing a single circuit including a directly connected single-voltage-source of low voltage alternating current, connections therefrom to the plate grid, the filament, the cathode and the supplemental grid of said electron discharge device such as to utilize said single-voltage-source for complete energization thereof, a metal core transformer, said single-voltage-source being connected in series with the primary of said transformer, the filament and the cathode, the secondary of the transformer being connected with said input circuit, means providing an output circuit including connection from the plate to said single circuit, and means for connecting said supplemental grid to said output circuit.

4. In a radio-receiving apparatus, an electron discharge device having an anode, a cathode, a grid and a filament, means providing a single circuit including a directly connected single voltage alternating-current-source together with connections therefrom to the anode, the grid and the filament of the electron discharge device such as to utilize said single voltage source for complete energization thereof, and an amplifying transformer, the primary of the transformer being connected in series with the cathode and in multiple with the anode and the filament, the secondary of said transformer being connected with said grid.

5. In a radio-receiving apparatus, an electron discharge device having a plate, a grid, a filament, and a cathode heated by said filament, means providing a single circuit including a directly connected single voltage alternating-current-source, together with connections therefrom to the plate, the grid, the filament and the cathode of said electron discharge device such as to utilize said single voltage source for complete energization thereof, and an amplifying transformer, the primary of the transformer being connected in series with the filament and the cathode, and in multiple with the plate to filament circuit, the secondary of said transformer being connected with said grid. 50

6. In a radio-receiving apparatus, an electron discharge device having an anode, a grid and a filament, means providing a single circuit including a directly connected single voltage alternating-current-source together with connections therefrom to the anode, the grid and the filament of the electron discharge device such as to utilize said single voltage source for complete energization thereof, an amplifying transformer, the primary of the transformer being connected in series with the filament and in multiple with the anode to filament circuit, the secondary of said transformer being connected with said grid, and means for adjusting the potential impressed upon the elements of the electron discharge device by said single voltage alternating-current source. 70 75

7. In a radio-receiving apparatus, an electron discharge device having a plate, a grid, a filament, a cathode heated by the filament, and a supplemental grid, means providing a single circuit including a directly connected single voltage alternating-current-source, together with connections therefrom to the plate, the grid, the filament, cathode, and the supplemental grid of said electron discharge device such as to utilize
- 5

said single voltage source for complete energization thereof, an amplifying transformer, the primary of the transformer being connected in series with the filament and the cathode and in multiple with the plate to filament circuit, the secondary of the transformer being connected with said grid, and means connecting the supplemental grid with said plate to filament circuit.
